J. W. PIPPIN.

UNDERREAMER.

APPLICATION FILED SEPT. 23, 1915.

1,187,171

Patented June 13, 1916.

UNITED STATES PATENT OFFICE.

JOHN WILLIAM PIPPIN, OF BROWNWOOD, TEXAS.

UNDERREAMER.

1,187,171.

Specification of Letters Patent. Patented June 13, 1916.

Application filed September 23, 1915. Serial No. 52,165.

To all whom it may concern:

Be it known that I, JOHN W. PIPPIN, a citizen of the United States, and a resident of Brownwood, in the county of Brown 5 and State of Texas, have invented a certain new and useful Improvement in Underreamers, of which the following is a specification.

My invention relates to improvements in under-reamers, and it consists in the combinations, constructions, and arrangements 10 herein described and claimed.

An object of the invention is to provide a tool of this class which is simple in construction, positive in action, and which embodies certain elements which give the tool 15 great strength, thereby preventing the breaking of the bits or cutters when reaming hard rock.

A further object of my invention is to 20 provide an under-reamer in which the bits are held positively in a contracted position while the tool is being lowered through a well casing, until the bits have passed the end of the casing, whereupon they will be 25 automatically expanded.

A further object of my invention is to 30 provide an under-reamer having expanding bits that do not require triggers or other similar devices, such as latches, to hold them in contracted position while passing through a well casing.

Other objects and advantages will appear 35 in the following specification, and the novel features of the invention will be particularly pointed out in the appended claims.

My invention is illustrated in the accompanying drawing forming part of this application, and in which—

Figure 1 is a side view of the device showing 40 it in operative position, certain parts of the device being shown in section. Fig. 2 is a longitudinal section through the device, showing the latter in the position it assumes when being lowered through the well casing. Fig. 3 is a side view at right angles to Fig. 1, showing the means of operating the bits, portions of the figure being shown in section. Fig. 4 is a section along the line 4—4 of Fig. 2. Fig. 5 is a section along the 45 line 5—5 of Fig. 2.

In carrying out my invention, I provide a body portion 1 which is provided with a threaded tapered extension 2 arranged to enter the socket of the usual drill rod 3. 50 The body portion has flat faces at 4 which

permit the manipulation of the body portion by means of a wrench.

As will be seen from the drawings the body portion 1 is provided with a slot 5 which extends through from one side to the other. The lower end of the body portion is provided with a socket 6 which is tapered as shown. A shoulder 6^a is formed in the walls of the socket near the bottom thereof. The body portion 1 extends below the socket 6 as shown at 1^a. The purpose of this extension will be explained later. The bits for this under-reamer are shown at 7 and 8 respectively. The upper end of each of these bits has a semi-conical extension like that shown at 8^a in Fig. 3, leaving a shoulder like that shown at 8^b. Each of the bits has a portion which is in engagement with the rounded lower end 9 of a rod 10. As will be seen from Fig. 5, the rounded ends have lateral extensions 9^a into which the ends of screws 11 extend, these screws having shoulders 11^a which fit up tightly against the extensions 9^a.

As will be seen from Fig. 5, each of the bits is provided with a recess on its inner side, these recesses being shown at 7^c and 8^c to admit the extensions 9^a. The bits are provided with oblong recesses 7^d and 8^d into which the heads of the screws 11 extend. Webs 7^e and 8^e are provided with openings which admit the screws 11. This construction gives the two bits a pivotal movement around the fulcrum head 9. The screws 11 however hold the bits to the head so that they do not fall apart when the tool is removed from the well.

The rod 10 passes upwardly through a bore 12 in the body portion 1 and the end extends into a bore 13. The rod 10 has a threaded portion 10^x upon which is mounted a collar 14 which is threaded to engage the threads 10^x and which may be adjustably moved along the rod 10. A spring 15 bears at one end on this adjustable collar or nut, and at the other end at the bottom of the slot 5. The tendency of the spring 15, therefore, it will be seen, is to force the rod 10 upwardly.

From the foregoing description of the various parts of the device, the operation thereof, may be readily understood.

In Fig. 2 I have shown a well casing 16 which is provided with a casing shoe 17 at its lower end. In inserting the tool in the 110

casing, the bits 7 and 8 are held together by means of a spring split ring 18. This ring will engage the top of the casing and will be held back while the tool will pass down into the interior of the casing. When the spring ring 18 passes off from the bits 7 and 8, the latter will engage the side walls of the casing as shown in Fig. 2, while the extensions 7^a and 8^a will engage the shoulders 6^a which are formed by the walls of the socket 6. This prevents any upward movement of the rod 10 and hence does not tend to expand the bits while the latter are being lowered through the casing. There is, therefore, no tendency to bind, and the tool may be easily lowered into place. In order to prevent the upper portions of the bits from spreading too far, I provide a screw 19 in one of the members provided with a lock 20, so that the lower portion of the other bit may be adjusted up close to the desired point, when passing through a casing of given size. It will be obvious that this screw 19 may be turned so as to adjust the bits for easily passing through casings of various sizes. The lock nut 20 holds the screw in its adjusted position.

When the bits pass the end of the casing, *i. e.*, the shoe 17 so that the outer sides of the bits are not now held inwardly by contact with the casing, the spring 15 tends to pull the rod 10 upwardly, and this forces inwardly the upper ends of the bits until they ride off from the shoulder 6^a and into the tapered sockets 6 into which the upper ends of the bits are suddenly and forcibly drawn by means of the spring. The apparatus is now in the position shown in Fig. 1, that is to say, the bits have been expanded so as to continue the cutting or under-reaming of the bore.

In order to compress the spring 15 and to move the rod 10 downwardly, thereby forcing the upper ends of the bits out of the socket 6, I provide a handle or lever 21 to which is connected a bent link 22, the latter having an end which enters the slot 5 and which surrounds the rod 10 and bears on the nut or collar 14.

It will be seen that I have provided an expanding bit which is held rigidly in position while it is being inserted and is passing through the casing, but which will expand automatically when the end of the casing is reached. The device is simplified in that the spring 15 which exerts tension on the rod 10, tends to hold the upper end of the bits against the shoulder 6^a as explained, and also tends to draw the bits into the tapered socket when the bits have cleared the end of the casing. It will also be noted that the screws 11 may be screwed up tight against their shoulders 11^a so there will be no danger of their coming out. The heads 65 of these screws are countersunk in the open-

ings 7^a and 8^a and therefore they are never in danger of coming into contact with the walls of the casing.

Another feature to which I desire to call attention is the fact that, the shoulders 7^b and 8^b are forced up into engagement with the shoulders 6^a, these latter shoulders being the same that engage the upper ends of the bits to hold the latter in position when the bits are being passed through the casing. The nut 14 is fastened by a pin to the rod 10 so it cannot work away from the proper position. The spring 15 is compressed when the bits are out of the socket and the rod is in its lowest position. This prevents the bit top points from being pulled out below the lower end of the extension 1^a, which as will be seen forms virtually a sleeve projecting below the socket and which keeps the bits from spreading apart at their upper ends and leaving the socket entirely.

I claim:

1. An under-reamer having a body portion provided with a slot, a spring disposed within the slot, a longitudinal bore disposed centrally of the body portion and intersecting the slot, a movable rod disposed in said bore, said body portion having a tapered socket at its lower end and said spring being arranged to bear upon a portion of the rod to hold it normally in an upper position, a plurality of pivotally mounted bits carried at the lower end of said rod, said body portion being provided with a shoulder adjacent to the lower edge of the socket adapted to be engaged by the upper portions of the bits for preventing the expansion of the same, and means for spacing the lower ends of the bits apart.

2. An under-reamer comprising a body portion having a central longitudinal bore, a transverse slot intersecting said bore, a longitudinal rod disposed within said bore, bits fulcrumed on the end of said rod, means carried by the rod for preventing the displacement of the bits, said body portion having a tapered socket at its lower end, and being provided with shoulders adjacent to the lower end of the socket, and a set screw carried by one of said bits for spacing the bits apart.

3. In an under-reamer, a cylindrical body portion provided with a central bore, a transverse slot arranged to intersect said central bore, a longitudinally movable rod disposed within said slot, a fixed nut carried by said rod, a spring surrounding said rod and arranged to bear at one end on said nut and at the other end on the end wall of the slot, said body portion having a tapered socket near its lower end, said lower end being provided with a cylindrical sleeve-like extension and having a shoulder adjacent the lower end of said socket, bits fulcrumed on the lower end of said rod,

each of said bits being provided with an opening, a screw arranged to extend through each of said openings into the rod, the heads of the screws preventing the displacement of the bits from the rod.

5 4. In an under-reamer, a body portion provided with a central bore and having a tapered socket, a rod disposed within said central bore and being provided at its end 10 with a pair of oppositely extending screws, a plurality of bits each of said bits having a recess on one side arranged to pivotally engage a portion of the rod, and a recess on the opposite side registering with said 15 first-named recess, thereby leaving a web between the two recesses, said web being provided with an opening arranged to receive the body portion of the screw, the head of the screw engaging a portion of the web, thereby preventing displacement of the bits.

20 5. In an under-reamer, a body portion provided with a central bore and having a tapered socket, a rod disposed within said central bore, and being provided at its end 25 with oppositely extending screws, a plurality of bits, each of said bits having a recess on one side arranged to pivotally engage a portion of the rod, and a recess on 30 the opposite side registering with said first

named recess, thereby leaving a web between the two recesses, said web being provided with an opening arranged to receive the body portion of the screw, the head of the screw engaging a portion of the web, thereby preventing the displacement of the bits, one of said bits being provided with an adjustable set screw for spacing the lower portions of the bits apart.

35 6. In an under-reamer, a body portion 40 provided with a central bore, said body portion having a cylindrical extension at its lower end, and a tapered socket extending upwardly above said cylindrical extension, and a shoulder disposed at the lower end of 45 said tapered socket and at the upper end of the inner wall of the cylindrical extension, a longitudinally movable rod disposed within said central bore, bits fulcrumed on the lower end of said rod, the upper ends of the 50 bits being arranged to engage the inner walls of the cylindrical extension when the movable rod is in its lower position, thereby preventing the displacement of the bits, and means for spacing the lower portions of the 55 bits apart.

JOHN WILLIAM PIPPIN.
